UNITED STATES PATENT OFFICE.

JOHN A. HILL, OF LAFAYETTE, INDIANA.

CUTTER-BOARD FOR PAPER-HANGERS.

SPECIFICATION forming part of Letters Patent No. 794,013, dated July 4, 1905.

Application filed July 2, 1904. Serial No. 215,189.

To all whom it may concern:

Be it known that I, JOHN A. HILL, of Lafayette, county of Tippecanoe, and State of Indiana, have invented a certain new and useful Cutter-Board for Paper-Hangers; and I do hereby declare that the following is a full, clear, and exact description thereof, reference being had to the accompanying drawings, in which like numerals refer to like parts.

The object of this invention is to improve the construction of cutter-boards for paper-hangers.

The object is to make a cutter-board that is considerably more lasting and more convenient and at the same time firmer than the cutter-boards in general use.

Broadly speaking, these objects are accomplished by mounting a zinc strip upon a metallic base. By surrounding a metallic base—such, for example, as a strip of galvanized iron—with a layer of zinc a complete and permanent cutter-board is provided with a zinc cutting-surface on each side and with a metal base for supporting said cutting-surface.

The nature and advantages of the invention will be understood from the accompanying drawings and the following description and claims.

In the drawings, Figure 1 is a perspective view of the cutter-board with a straight-edge and cutter thereon, showing the position of the cutter-board while in use. Fig. 2 is a transverse section of the cutter-board, drawn on an enlarged scale.

In detail, 10 is a paper-cutter, and 11 a straight-edge or guiding-strip for the cutter. The knife 12 of the cutter rolls upon and cuts the sheet of paper beneath the straight-edge or guide for the cutter and upon the cutting-board below. The cutting-board, therefore, serves as a base or solid smooth support upon which the paper may be cut by the rotary knife passing over it. The cutting-board consists of a strip 15 of metal, preferably flexible and resilient, like galvanized iron, about eight feet long and four inches wide. A layer 16 of zinc is superimposed upon the metal strip and preferably surrounds it, so that there will be a zinc layer on both sides there-

of. I have mounted the layer of zinc on the metal strip by cutting a strip of zinc of about the same dimensions as the strip of galvanized iron and placing upon the hard-metal strip and cutting another strip of zinc wider than the first and placing it under the strip of iron and bending the lateral edges over the edges of the strip of iron and the strip of zinc above and securing the overlapping edges 60 of the wide strip of zinc to the strip of zinc below. In this way the layer of zinc surrounds the hard-metal strip like an envelop and furnishes two cutting-surfaces in addition to covering the hard-metal plate. The hard-metal plate or base prevents the zinc yielding under the pressure of the cutter. It is this yielding of the zinc under the pressure of the cutter when the zinc is placed on a yielding base, such as a wooden base, that 70 causes the knife to cut through the zinc and soon to destroy the zinc, because it became slit in many places. Zinc secured on a soft and yielding base must be renewed very frequently. With this cutter-board the knife of 75 the cutter also cuts the paper more readily, as the zinc does not buckle or sink into the wood under it. With a hard-metal base the knife does not get through the zinc.

What I claim as my invention, and desire to 80 secure by Letters Patent, is—

1. The combination with a straight-edge and a paper-cutter for paper-hangers, of a cutter-board upon which the straight-edge may be placed consisting of a flexible and resilient hard-metal piece with a layer of zinc secured thereon.

2. The combination with a straight-edge and a paper-cutter for paper-hangers, of a cutter-board upon which the straight-edge 90 may be placed consisting of a flexible and resilient strip of hard metal, and a layer of zinc enveloping said strip, substantially as set forth.

In witness whereof I have hereunto affixed 95 my signature in the presence of the witnesses herein named.

JOHN A. HILL.
